UNITED STATES PATENT OFFICE.

ROBERT C. PIERCE, OF TALLMADGE, OHIO, ASSIGNOR TO THE B. F. GOODRICH COMPANY, OF NEW YORK, N. Y., A CORPORATION OF NEW YORK.

GROMMET-WINDING MACHINE.

1,415,696.

Specification of Letters Patent.

Patented May 9, 1922.

Application filed December 7, 1921. Serial No. 520,522.

To all whom it may concern:

Be it known that I, ROBERT C. PIERCE, a citizen of the United States, residing at Tallmadge, in the county of Summit and 5 State of Ohio, have invented a certain new and useful Grommet-Winding Machine, of which the following is a specification.

This invention relates to adjustable forms and, more particularly to means for changing 10 the size of an annular work-receiving space such, for example, as is present in grommet winding machines of the general type described in U. S. Patent No. 1,294,160 of February 11, 1919, to A. C. Pratt, and 15 in my co-pending application Serial No. 499,961, filed September 12, 1921.

In such machines a wire is fed into an annular form from a spool carried by a ring winder, the wire being pushed circumferentially around in the form by a set of wire-feeding rollers. The ring winder may also 20 carry a die or "quill" formed with a spiral passage through which the wire is forced by the wire-feeding rollers as it passes to 25 the form, the wire thereby being given a permanent spiral form causing it to adjust itself to, and to retain, its proper position in the body of the grommet. The usual practice is to feed into the annular channel 30 of the form a sufficient length of straight wire to form a core for a grommet and then to spiral the wire as it passes into the form to build the sheath or body of the grommet upon the core. It heretofore has been 35 known that the straight wire for the core may be obtained by feeding the wire through the die with the ring winder stopped if the wire in the form, at the delivery end of the die, be held against turning on its own axis, 40 the wire in this case not being permanently deformed although passing through the die.

The general object of my invention is to provide improved means for changing the size of the work receiving space of a 45 form, and more particularly of an arcuate space such as is employed in machines of the character above referred to, wherein, for example, the work receiving space of the form first determines the curvature of the core 50 of the grommet and must then be enlarged to correspond to the increased diameter of the complete grommet. A further object is to provide means adapted automatically to

change the size of the work-receiving space in predetermined relation to the progress 55 of the work.

Of the accompanying drawings:

Fig. 1 is a plan view, with parts broken away, of a grommet winding machine embodying a preferred form of my invention, 60 showing the parts in position for forming the core of a grommet, and a partially formed grommet therein.

Fig. 2 is a plan view of a part of the same with the work-receiving space enlarged to 65 accommodate the full-sized grommet, the latter being shown therein.

Fig. 3 is a detailed plan view, partly in section, of one end of the form.

Fig. 4 is a section on line 4—4 of Fig. 1. 70

Fig. 5 is a plan view of the grommet as formed by the machine.

Fig. 6 is a side elevation of the machine, with parts broken away.

Fig. 7 is a reverse plan view, with parts 75 broken away, of the form-supporting member.

Fig. 8 is a fragmentary section on line 8—8 of Fig. 1.

The grommet as it leaves the machine may 80 comprise an arcuate core strand A (Fig. 5), an integral body portion B, of the same wire, wound helically about said core section and about an empty core space which with said arcuate core strand completes a circle, and 85 an integral length C of straight wire, at the last-wound end of spiral wire, adapted to be forced in between the spiraled convolutions by hand to occupy said core space and complete the core, the finished product being 90 a grommet composed of a single wire, the end portions thereof lying within the body of the grommet and constituting a core therefor.

After winding the body of a grommet, 95 comprising usually six convolutions of spiraled wire lying in contact with each other about the arcuate core strand and the empty core space, it is the usual practice to stop the ring winder, while the wire feeder continues to feed into the form a length of straight wire sufficient to fill the empty core space of the last grommet and provide the arcuate core section of the next grommet, the core wire being prevented from assuming 105 the permanent spiraled form by its in-

tegral connection with the last-wound grommet, which holds it against turning on its own axis.

10 is a stationary plate constituting a part 5 of the frame of the machine and having the form of an incomplete annulus or crescent. Mounted upon this plate are a pair of lower form members 11, 12 each having, in plan, the form of a half of a crescent, the one 11 10 at the rear of the machine being secured to the plate 10 and the front one, 12, pivotally surrounding a rock-shaft 13, on the outer margin of the plate 10, being thus adapted for sliding movement on said plate. 14 is 15 an adjusting screw swiveled in a block 15 secured to the under side of the plate 10, for moving the form member 12 on the plate 10 to adjust it for different sized grommets.

The lower form members 11, 12 provide 20 the floor of the work-receiving cavity and each is formed with an upturned flange 16 (Figs. 1 and 4), around its inner periphery, constituting the inner wall of said cavity. Upon said lower form members respectively 25 are slidingly mounted a pair of arcuate upper form members 17, 18, of L-shaped cross-section, providing the outer wall and roof of the work-receiving cavity, said members 17, 18 being of substantially the same 30 form, in plan, as the lower form members and being pivoted on the latter at 19 and 13 respectively.

Lying within the part of the work-receiving cavity formed by the front form members 12 and 18 is a metal tape 20 having one 35 end secured to the end 21 of the member 18 and its other end passing partly around and being secured to a variable-radius, cam-shaped arm 22 mounted between the form 40 members 12 and 18 and secured to a vertical pivot-pin 23 journaled in the upper form member 18, so that turning the variable-radius arm 22 counter-clock-wise, as viewed in Figs. 1 and 2, tightens the metal tape 20 45 and causes it to decrease the size of the work-receiving space, and a reverse movement has the opposite effect, the distance between the flange 16 and the arm 22 also changing by reason of the several working 50 radii on the latter. The straight wire constituting the core of the grommet is shown at 24 (Fig. 1), with a few turns of spiral wire wound thereon and gripping the same. The parts as there shown are in closed position, the tape 20 being held by the arm 22 55 close to the inner flange 16 at the pivot end of the member 12, while in Fig. 2 the arm 22 has been turned clock-wise to pay out the tape and thereby enlarge the work-receiving space to accommodate the full-sized grommet, 25.

Another metal tape 26 (Figs. 3 and 4) is mounted in the upper rear form member 17, one end of said tape being secured to a 60 variable-radius arm (not shown) corre-

sponding to the arm 22 and secured to a pivot-pin 27 journaled in said form member 17.

To secure an approachment of the tape 26 to the inner flange 16 of the lower, rear 70 form member 11 at the free end of said member as well as at other points, when the tape is tightened, and thereby to hold the grommet core closely to circular form, I prefer to fold the end of the tape back upon 75 itself and attach its reversed end portion 28, which thus functions as a leaf spring, to the form member 17, as shown in Fig. 3. I do not wholly limit my claims, however, to an integral relation of the parts 26 80 and 28.

The pivot pins 27 and 23 are provided with arms, which respectively are shown at 29 in Figs. 1 and 2 and at 30 in Fig. 6, said arms being connected by links 31, 31 85 with lever-arms 32, 32 secured to rock-shafts 13 and 19 journaled in pivot sleeves, one of which sleeves is shown at 13^a in Fig. 8, upon which the lower form member 12 and the upper form members 17, 18, turn, 90 said shafts extending downward through the plate 10 and being provided below with lever-arms 33, 33 (Fig. 7) having their outer ends adjacent each other and pressed against a bracket 34 on a bar 35 by the action of a 95 tension spring 36 connecting the arms 32 (Figs. 1 and 2).

The bar 35 (Fig. 7) has a slotted end slidably mounted upon a stud bolt 37, and its other end is hinged to one arm of a lever 100 38 pivoted at 39 on the under side of the plate 10, the other arm of said lever being connected by a link 40 with an arm 41 secured to a vertical rock-shaft 42. The latter is journaled in the frame of the machine 105 and provided at its lower end with a cam finger 43 adapted to be engaged by a laterally-acting cam 44 on a cam drum 45 to rock said shaft and, through the connections just described, to rotate the variable radius-arm 22 and its mate toward each other and so hold them, against the action of spring 36, to tighten the tapes 20 and 26 and thus 110 restrict the work-receiving space during the passage of said cam past the finger. The 115 cam drum 45 is provided with other cams (not shown) for timing the operation of the ring winder and the wire feeding rollers.

52, 52 are spring latches engaging the heads of stud bolts 53 mounted in the lower 120 form members 11, 12, to hold the upper form members 17, 18 in position during the winding of the grommet, each latch being connected by a link 54 with a thumb lever 55 adjacent a handle 56 on the form member, 125 by which handles the form members may be slid outward onto a pair of supporting ears 57, 57 formed on the lower form members, to open the form for the removal of the finished grommet, the upper form mem- 130

bers, when so opened, taking the positions indicated by dot-and-dash lines in Fig. 1.

The preferred mechanism here shown for feeding the wire into the form is known in the art but may be briefly described as comprising a peripherally supported ring winder 46 provided with a driving gear 47 and carrying a wire spool 48 and a set of wire-feeding rollers 49, 49, driven through intermediate gears and shafts from a gear (not shown) formed on the rear end of a sleeve 149, journaled concentrically in the ring winder 46 and formed with a gear 50 on its front end by which it is driven in the same direction as the winder but at a higher speed. 51 is the die through which the wire is forced by the rollers 49, giving it the spiral form when the ring winder 46 is turning.

20 The starting and stopping of the winder and the wire-feeding rollers may be controlled by suitable cams on the drums 45 in the manner described in my aforesaid co-pending application.

25 58 is a compensating counter-balance for the wire spool 48, such as is described in the co-pending application Serial No. 493,257 of Harvey L. Young.

59 is a stationary, two-part, hinged funnel, in the gap of the form, for directing the wire from the die 51 into the form. 60 is a worm wheel through which the cam drum 45 is driven, counter-clockwise as viewed in Fig. 6, to time the operation of the ring winder 46 and the wire-feeding rollers 49, as well as the form-adjusting mechanism above described.

In the operation of the machine, the upper form members 17, 18 being opened out on the ears 57, exposing the last-wound grommet and a complete circle of plain or non-spiraled wire integral therewith and with the wire on the spool 48, said non-spiraled wire is severed relatively near its junction with the spiraled body of the grommet and the latter is removed from the form, in which is left preferably about three-fourths of a circle of non-spiraled wire extending from the die 51. The form is then closed and the machine started, the ring winder feeding spiraled wire into the form while the cam 44, through the finger 43, variable-radius arms 22, and intermediate parts, holds the metal tapes 20, 26 taut, constricting the work-receiving space to control the size of the grommet core. When the end of the non-spiraled wire reaches the funnel 59, the spiral wire begins to be laid thereon, and when the core-end with the spiraled wire thereon is crowded into the work-receiving space and reaches approximately the position shown in Fig. 1, the cam 44 leaves the finger 43 and permits the spring 36 to turn the arms 22, releasing the tapes 20, 26, and thereby enlarging the work-

receiving space to accommodate the increased diameter of the work due to the addition of the spiraled convolutions to the core. When the work-receiving space is thus enlarged the core itself does not correspondingly enlarge by springing out against the outer wall of said space because its end is gripped by the first few turns of spiraled wire laid thereon, holding it to its original circumference.

75 The ring winder then continues to lay spiraled wire on the core and about the empty core space constituting the rest of the circle, until the body of the grommet is completed. The ring winder then stops 80 while the wire-feeding rollers 49 continue to feed a complete circle of non-spiraled wire into the form. The form is then opened, the non-spiraled wire severed as before, and the operation is repeated, the cam drum being freed from the driving mechanism of the machine and turned by hand after the finished grommet is removed, to bring the cam 44 into operation and again restrict the work-receiving space.

85 While the rigid form members 11, 12 and 17, 18 coact with the tape to preserve its substantially circular form under pressure of the work, this effect is also secured by the action of the variable-radius arm 22, which 90 shortens and lengthens the chord as well as the arc defined by the tape.

95 Modifications may be resorted to without departing from the scope of my invention, and I do not wholly limit my claims to the 100 specific construction here shown.

I claim:

1. In a machine of the character specified, the combination of a form for giving wire an annular shape, means for feeding wire into said form, and mechanism timed with the wire-feeding means for automatically varying the effective diameter of said form.

105 2. In a grommet-winding machine, the combination of a ring winder, a wire-spool carried thereby, a form enclosing a curved work-receiving space, means for feeding wire from said spool into said space, a timing device, and means controlled by said device for enlarging said space.

110 3. In a grommet-winding machine, the combination of a ring winder, a wire spool carried thereby, a form enclosing a curved work-receiving space, means for feeding wire from said spool into said space, a wire-spiraling die carried by the winder, a cam drum for timing the operation of said winder and wire-feeding means, and means controlled by said drum for enlarging said work-receiving space in predetermined relation to the operation of said ring winder.

115 4. In a machine of the character specified, the combination of a form for giving wire an annular shape, said form including a curvilinear tape, and means for adjusting 120

125

130

said tape to vary the effective diameter of said form.

5. In a grommet-winding machine, an adjustable form comprising a metal tape constituting an outer wall of a curvilinear work-receiving space, and means for pulling and slackening said tape to change the length of said work-receiving space.

6. In a grommet-winding machine, an adjustable form comprising a rigid member constituting an inner wall of a curvilinear work-receiving space, a flexible tape constituting an outer wall of said space, and means for pulling and slackening said tape to change 15 the size of said work-receiving space.

7. In a grommet-winding machine, an adjustable form comprising a rigid member constituting an inner wall of a curvilinear work-receiving space, a flexible tape constituting an outer wall of said space, and a variable-radius arm for pulling and slackening said tape to change the size of said work-receiving space.

8. In a grommet-winding machine, an adjustable form including a flexible tape constituting an outer wall of a curved work-receiving space, and means adapted to pull said tape to shorten its effective length while bringing the virtual ends of said tape nearer 30 each other substantially to preserve its degree of curvature.

9. In a grommet-winding machine, an adjustable form comprising a pair of rigid members adapted together to define a curvilinear work-receiving cavity and separable to open said cavity, a flexible tape lying in said cavity, and means for pulling and slackening said tape.

10. In a grommet-winding machine, an adjustable form comprising an outer form member, a leaf-spring having one end secured thereto, a flexible tape secured to the free end of said spring and constituting an outer wall of a curvilinear work-receiving 45 space, and means for pulling said tape against the tension of said spring.

11. In a grommet-winding machine, an adjustable form comprising an outer form member, a leaf-spring having one end secured thereto, a flexible tape secured to the free end of said spring and constituting the outer wall of a curved work-receiving space, and a variable-radius cam-shaped arm for pulling the tape against the tension of said 55 spring to reduce the size of said work-receiving space.

12. In a grommet-winding machine, an

adjustable form comprising a structure forming a floor and inner wall of a curved work-receiving cavity, a pair of curved upper form members pivoted at adjacent points on said structure and forming a roof and outer wall of said cavity, a pair of flexible tapes in said cavity having their outer ends connected with said form members respectively, shafts journaled concentrically with the pivots of said form members, and means operatively connected with said shafts for pulling and slackening said tapes.

13. In a grommet-winding machine, the combination of grommet-winding mechanism, a form for the grommet having an adjustable tape for varying its effective size, and means timed with said winding mechanism for automatically adjusting said tape.

14. In a grommet-winding machine, an adjustable form comprising a structure forming a floor and inner wall of a curved work-receiving cavity, a curved upper form member pivoted on said structure and forming a roof and outer wall of said cavity, a flexible tape in said cavity having one end connected with said form member, a shaft journaled concentrically with the pivot of said form member and connected with the other end of said tape, means operatively connected with said shaft for pulling and slackening said tape, mechanism for winding a grommet contained in the form, and means for automatically turning said shaft in predetermined relation to the operation of the winding mechanism.

15. In a grommet-winding machine, the combination of grommet-winding mechanism, a grommet-sizing and holding form comprising a pair of substantially semi-circular sections between which the winding mechanism operates, and means timed with said mechanism for automatically enlarging said form at a predetermined stage.

16. In a grommet-winding machine, the combination of grommet-winding mechanism, a form comprising a pair of substantially semi-circular sections having grommet-sizing tapes between which the winding mechanism operates, and means timed with said winding mechanism for automatically slackening said tapes to enlarge the working space at a certain stage in the formation of the grommet.

In witness whereof I have hereunto set my hand this 29 day of November, 1921.

ROBERT C. PIERCE.
